INDENTING MACHINE

Irving E. Booth, Rochester, N. Y., assignor to
 United Shoe Machinery Corporation, Flemington, N. J., a corporation of New Jersey

Application September 1, 1943, Serial No. 500,747

9 Claims. (Cl. 12—32)

This invention relates to indenting machines and is herein illustrated and described as embodied in a machine for making indentations or imitation stitches upon the upper surface of the projecting edge of a shoe sole.

This upper surface is often very resistant to pressure, particularly so in the case of welted shoes where the welt is reinforced by the stitching which joins it to the outer sole, and considerable force is needed to produce satisfactory, deep impression by means of the indenting tool, which consists of a freely rotatable toothed roll arranged to act upon the surface of the welt or sole extension while the latter is held upon a work support.

It is recognized by those skilled in the art of welt indenting with a tool of the type mentioned above that the best results are obtained by causing the indenting pressure to be applied by a rapid succession of impulses of the indenting tool in addition to a steadily exerted pressure, as the shoe is fed steadily over the work support past the tool. The problem of operating in this manner is made difficult by the fact that the sole extension is often not of uniform thickness all the way around the shoe, and this is particularly true in the case of a welted shoe, wherein the thickness of the combined sole and welt is usually somewhat greater around the toe than along the sides of the forepart.

Attempts have been made to impart a rapid series of pressure impulses to the tool in welt indenting machines by means of a rotary hammer operated to strike a rapid succession of blows upon a reciprocable slide which carried the tool. Because of the high speed at which the hammer had to be operated in order to produce the desired results on the work, the operation of such machines was accompanied by an almost intolerable amount of noise and vibration which affected the operator so seriously that he was unable to work continuously.

By the use of a carefully constructed crank-driven toggle mechanism I have succeeded, in a machine disclosed in Letters Patent of the United States No. 2,248,058, granted July 8, 1941, upon my application, in providing a machine which runs smoothly and much more quietly than the rotary hammer machines mentioned above. In my patented machine, however, an operating mechanism is connected directly to a tool carrying slide which, as in prior machines, reciprocates in a straight line, and it is possible for the tool, which has a fixed stroke, to be lifted out of the indentation or indentations being formed

and to fail to enter them accurately upon the return stroke. This may produce imperfect work and, in order to prevent such occurrences, it is desirable that the tool remain continuously in contact with the work while the indenting operation progresses around the shoe.

With the foregoing in view, it is an object of the present invention to provide an indenting machine in which the tool will remain in the indentations being produced as the shoe is being fed past the tool while nevertheless a continuous rapid series of impulses is imparted to the tool with a minimum of shock or impact, thereby avoiding a fatiguing amount of noise and vibration.

Accordingly, I have provided a vibratory tool carrier operated by mechanism comprising a plunger arranged to engage the carrier, a toggle connected to the plunger, and means for straightening and breaking the toggle in rapid succession to cause the tool to exert pressure impulses upon the work. The plunger is preferably reciprocable in a fixed path and is entirely separate from the tool carrier so that the tool is not lifted out of the indentations being formed in the work.

In order to follow variations in the thickness of the work the work support in the illustrated machine is yieldingly sustained by a spring but is sufficiently heavy to have considerable inertia. This arrangement causes the tool to bear constantly on the stock while the machine is in operation and the inertia of the work support gives it the characteristics of an anvil, preventing undue yielding under the stroke of the plunger or rising between the rapidly consecutive strokes of the plunger on the tool carrier while readily permitting the relatively slow self adjustment of the work support to the thickness of the work as the point being operated upon progresses around the shoe. The combination of elements in the machine of the present invention makes it possible to produce deep indentations of high perfection and great uniformity very easily and rapidly.

These and other features of the invention will now be more fully set forth in the following specification to be read with reference to the accompanying drawings, in which

Fig. 1 is a side elevation, partly in section, of an illustrative machine embodying the invention;

Fig. 2 is a front elevation of the indenting roll and the mechanism for imparting pressure impulses thereto;

Fig. 3 is a plan view of the mechanism for driving the work table;

Fig. 4 is an enlarged view of the parts shown in the lower portion of Fig. 2;

Fig. 5 is a sectional view taken on the line V—V of Fig. 4;

Fig. 6 is a sectional view taken on the line VI—VI of Fig. 1;

Fig. 7 is a detail showing of the mechanism for adjusting the work table; and

Fig. 8 is a view in perspective of a portion of a shoe illustrating the operation performed by the machine.

The operating instrumentalities of the illustrated machine consists of an idly rotating toothed indenting roll 10 (Figs. 1 and 2) and a driven rotary work table 12. These members are carried by a frame having a hollow column 14 adapted to rest upon the floor. A housing 16 mounted on the top of the column 14 contains mechanism, later to be described, for imparting pressure impulses to the indenting roll.

The indenting roll 10 is provided with teeth for producing impressions I (Fig. 8) in the welt or sole extension of a shoe S. It is frusto-conical in form and is idly mounted for rotation upon a pin 18 (Fig. 4) clamped in the outer end of an arm or lever 20. The pin 18 is received within a longitudinal bore in the arm 20, the adjacent portion of the arm being slit and provided with a clamping screw 22 which, when tightened, causes the pin to be gripped within the bore. The inner end of the arm 20 is pivotally mounted for free swinging movement upon a pin 24 (Fig. 1) carried by a bracket 26 secured upon the top of the column 14. A stop 28 (Figs. 4 and 5) in the form of a permanent magnet mounted upon a block 30 engages the undersurface of the arm 20 to limit downward movement of the indenting roll 10. This magnet is preferably of the type which retains its magnetism even after being subjected to repeated shock. The magnet 28 has the shape of a square-cornered U of which the two upstanding branches are numbered 29 and 31. The block 30 is secured upon a pin 32 which in turn is carried by a bracket 34. A clamping screw 36 secures the bracket 34 to a portion of the column 14 in any desired position of heightwise adjustment. A vertical tongue-and-groove connection 37 is provided between the bracket 34 and the housing 14 to enable such adjustment to be made. The arm 20 is urged downwardly by a coil compression spring 38, the upper end of which bears against a bridge 40 on the lower portion of the housing 16 and the lower end of which bears against the arm 20. A stop screw 42 threaded through the bridge 40 and secured in adjusted position by a locknut 44 engages the upper surface of the arm 20 to limit the upward movement of the arm. The stop screw 42 extends within the spring 38 to support and guide the spring. While the weight of the arm 20 together with the force of the magnet might be sufficient without the spring 38, I prefer to use the spring also to hold the tool 10 downwardly against the work. Depending from the bridge 40 are a pair of lugs 43 in which are idly mounted a pair of guide rolls 45 which engage finished surfaces on the opposite sides of the arm 20 to insure lateral stability.

The mechanism for imparting pressure impulses to the arm 20 comprises a plunger 46 (Figs. 1 and 2) guided by a bushing 48 secured in a boss 50 formed in the housing 16. Secured upon the lower end of the plunger 46 is a cap 52 having a rounded head 54 which engages a cup-shaped depression formed in a block 56 secured upon the

upper surface of the arm 20. It should be noted that the plunger 46 is unconnected with the arm 20 and that while downward movements of the plunger may operate positively upon the arm, upward movements of the plunger do not draw the arm upward. The upper end of the plunger 46 is pivotally connected by a pin 58 to the lower end of a toggle link 68, the upper end of which toggle link is pivotally connected by a pin 70 to the lower end of a second toggle link 72. A stationary pin 74 secured in the housing 16 provides a pivotal support for the upper end of the link 72. Pivotally mounted upon the intermediate toggle pin 70 is one end of a connecting rod 76. The other end of the connecting rod 76 is mounted upon a crank pin 78 secured eccentrically upon a disk 80. A shaft 82 secured in spaced bearings 84 on the housing 16 carries the disk 80 and is driven by a pulley 86 mounted on the shaft 82 between the bearings 84. A belt 88 drives the pulley 86, and the resulting rotation of the shaft 82 operates through the connecting rod 76 to straighten and break the toggle formed by the links 68 and 72 twice for each complete rotation of the shaft.

The heightwise movement of the indenting tool 10 is not in a strictly vertical path but is inclined from the vertical at an angle of about 20°. Such inclination is obtained by providing bearings for the pin 24 having their common axis inclined at a similar angle to the horizontal. The axis of the pin 24, while thus inclined, lies in a vertical plane and is normal to a line parallel to the axis of the tool 10. The above-mentioned vertical plane which contains the axis of the pin 24 is parallel to the direction of feed of the work.

The work table 12 (Figs. 1 and 6) is in the form of an inverted cup which is supported internally for rotation upon a ball bearing 90 carried by a bracket 92. A cylindrical block 93 secured to the bracket 92 supports the inner race of the bearing 90. The under surface of the cap of the work table is supported by the balls which in turn are supported by the upper surface of the bracket 92. A post 95 threaded into the bracket 92 has a head which is countersunk into the working face of the work table to hold the work table down. This post engages the work table loosely enough to avoid interfering with the rotation of the work table. Extending from the periphery of the depending cylindrical flange portion 91 of the work table 12 are gear teeth 94 which are engaged by a pinion 96 carried by a shaft 98 journaled in the bracket 92. A housing 100 secured upon the upper surface of the bracket 92 surrounds the pinion 96 and the gear teeth 94. The bracket 92 has formed thereon an arcuate slide portion 102 which engages an arcuate guideway formed in a block 104. The center of the slide 100 and its guideway is positioned in the approximate locality of operation which is at the marginal portion of the upper or work supporting surface of the work table and directly below the indenting roll 10. A clamping screw 106 threaded into the bracket 92 and extending through an arcuate slot 108 formed in the block 104 serves to hold the bracket 92 in any desired position of angular adjustment. The block 104 is slidably mounted for heightwise movement upon a stem 110 (Figs. 1 and 7) with provision for heightwise adjustment thereon. Such adjustment is effected by a nut 112 threaded upon a portion of the stem 110 and having gear teeth 114 formed upon its periphery. Finished surfaces formed upon the upper and lower faces of the nut 112

bear against similar surfaces on the block 104 to control the heightwise position of the block on the stem. Rotation of the nut 112 is effected through a gear 116 meshing with the gear teeth 114. The gear 116 is carried by a stem 118 journaled in bearings 120 carried by the block 104 and having a knurled wheel 122 pinned upon its outer end portion. The lower end of the stem 110 rests in a socket or bushing 124 sunk into the upper portion of a heavy cylindrical block 126. The lower end portion of the block 126 has formed therein a socket 128 which is slidably engaged by the upper end of a treadle rod 130. Surrounding the treadle rod 130 is a coil compression spring 132, the upper end 15 of which bears against the lower end of the heavy block 126 and the lower end of which bears against a washer 134 which is backed up by a nut 136 threaded for adjustment upon the treadle rod 130. A collar 138 secured upon the treadle rod 20 130 engages a flange 140 on the column 14 to support the weight of the block 126, the work table 12, and the associated parts. The collar 138 rests normally upon the flange 140 with the work table 12 below operating position. The treadle 25 (not shown) is so arranged that the operator by depressing it can raise the rod 130 and thus yieldingly, through the spring 132, raise the heavy block 126 and the work table 12 into operating position. If desired, a stop may be provided for limiting upward movement of the work table to prevent the work table from being moved into engagement with the indenting tool 10 when no work piece is in position for operation. For guiding the block 104 there is provided a link 142 pivotally mounted at one end upon a stationary pin 144 carried by a pair of arms 146 depending from the bracket 26. The opposite end of the arm 142, which is forked, embraces a lug 148 extending from the block 104 and is pivotally secured thereto by a pin 150. Angular movement of the arm 142 about its pin 144 is relatively slight and the displacement horizontally of the pin 150 resulting from such movement is negligible. The arm 142 has a long bearing on the pin 144 to insure lateral stability.

The work table 12 and the mechanism for causing the indenting roll 10 to exert pulsating pressure upon the work are driven through mechanism which will now be described. Secured upon a bracket 152 (Fig. 1) mounted on the column 14 is a housing 154 (see also Fig. 3) in which is journaled a main shaft 156. Secured upon an end of the shaft 156 which extends outside of the column 14 is a pulley 158 driven by a belt 160 from any suitable source of power. Secured upon the opposite end of the shaft 156 within the column 14 is a pulley 162 which drives the belt 88 for operating the toggle mechanism which imparts pulsating pressure to the indenting roll. Also journaled in the housing 154 is a counter-shaft 164 which is driven from the shaft 156 by gearing 166. Secured upon the counter-shaft 164 is a skew gear 168 which meshes with a skew gear 170 secured upon a shaft 172 which is journaled in a bearing 174 carried by the housing 154. The shaft 172 inclines upwardly from the gear 170 in a vertical plane. An extensible shaft 176 is connected at its lower end by a universal joint 178 to the shaft 172 and at its upper end by a universal joint 180 to the lower end of the shaft 98 to drive the work table 12 in the direction of feed of the work.

A heating element 182 (Fig. 1) carried by a bracket 184 secured to the front cover plate of

the housing 16 is supplied with current by a pair of leads 186. The heating unit 182, which is stationary, is in close proximity to the indenting roll 10 and supplies heat to the indenting roll by radiation. To protect the upper of the shoe from the heat generated by the unit 182 and also from any danger of mechanical abrasion by the indenting roll 10, and for the additional purpose of guiding the shoe by contact with the upper, is a plate 188, the upper end portion of which is hinged upon a pintle 190 carried by a bracket 192. The plate 188 may be swung upwardly and outwardly to afford access to the heating unit or to the indenting roll. When lowered to its operating position it is held against inward movement by a pair of stop lugs 194 depending from the bracket 192. The bracket 192 is secured by a clamping bolt 196 to a lug 198 extending from the cover plate of the housing 16. The bolt 196 extends downwardly through a hole in the lug 198 and through a slot in the bracket 192, the lower end portion of the bolt being threaded through a nut 200. A horizontal adjusting screw 202 threaded into the lug 198 and having a circumferentially grooved head in engagement with a notch formed in an upstanding flange of the bracket facilitates accurate adjustment of the bracket, whereupon the bracket may be clamped by the bolt 196 in adjusted position.

The operation of the machine will now be described. While the machine is running idly, the indenting tool carrier 20 is resting upon the magnetic stop 28 which is just below the downward reach of the reciprocating plunger 46, and the indenting tool 10 is lying just above the work table 12 and out of contact with it. After introducing a work piece, the operator depresses the treadle to raise the work table through the spring 132 into operating position. The work piece thereupon engages the indenting roll 10, raising the carrier lever 20 into the path of the reciprocating plunger 46. The work table 12 will rise to a level at which the thrust of the spring 132 is balanced by the downward thrust of the spring 38, the weight of the various parts, and the continuous effect of the successive impulses of the plunger upon the carrier. The effective working compression of the spring 132 may be increased or diminished by raising or lowering the work table through the knurled wheel 122 or the nut 136 to vary the force exerted by the indenting roll upon the work. The inertia of the heavy block 126 is sufficient to prevent any appreciable vibratory movement of the work table 12 in response to the rapid reciprocation of the plunger 46. The indenting tool 10 is thus able, in the course of each down stroke of the plunger, to exert pressure against the work piece before the work table has time to yield downwardly. The pressure thus exerted increases progressively toward the end of the stroke and reaches a maximum at the end of the stroke. The maximum pressure, developed through the toggle mechanism, has an intensity which is particularly effective in the forming of indentations in such materials as leather. This pressure, it will be observed, is not obtained through the impact of a hammer blow but is built up gradually during each downward stroke of the plunger. The gradual application of the operating pressure, repeated in swift succession, is preferable to a series of hammer blows for, by avoiding shock and concussion, it enables the machine to run more smoothly and quietly, and with less wear. Even more important is the improved result upon the work piece,

for the gradually applied pressure attains a momentary maximum which exceeds that obtainable through hammer blows under practicable conditions of operation, and without damaging the work piece.

The work table 12, while held relatively stationary by the inertia block 126 against the rapid series of pressure impulses of the indenting tool, is nevertheless capable of a relatively slower up and down movement to compensate for the different thicknesses of work pieces or for variations in thickness in different portions of the same work piece, the combined effect of the inertia block 126 and the spring 132 being to make the work table self-adjusting for height while at the same time holding it effectively stationary against each down thrust of the indenting tool 10. The pressure exerted upon the work piece will therefore be uniform regardless of variations in the thickness of the work piece, and the resulting indentations will be of uniform depth. The pressure to which the work piece is subjected may, however, be varied by adjustment of the compression of the spring 132.

The fact that the plunger 46 is unconnected with the carrier 20 enables the indenting tool 10 to press at all times upon the work under the influence of the spring 38 and the weight of the carrier 20, since the plunger will not in the course of its upward movements lift the indenting tool from the work. Any likelihood of the indenting tool being lifted and then let down with its indenting teeth out of register with the indentations already formed is thus avoided. As a result the indenting tool will lie at all times upon the work piece with its teeth in the indentations already formed, and will exert a pulsating pressure of great momentary intensity that will leave clear, sharp, uniform indentations in the work piece.

The feed of the work piece is taken care of by the drive of the work table and also by the component of movement in the direction of feed which the indenting tool has by reason of its oblique path of movement. Although the indenting tool is freely rotatable, nevertheless the inertia of the tool is sufficient, in view of the rapidity of reciprocation, to cause the tool to exert an effective force in the direction of feed upon the work piece.

When the operator wishes to withdraw the work piece from the machine he releases the treadle to let the work table down. The carrier 20 at once drops and rests upon the stop 28 which, because of its magnetic properties, holds the carrier firmly against any tendency to rebound or to chatter in synchronism with the reciprocating plunger 46.

Having thus described my invention, what I claim as new and desire to secure by Letters Patent of the United States is:

1. An indenting machine, comprising an indenting tool, a carrier for said tool mounted for operative movement to enable the tool to press against a work piece, a member unconnected with said carrier but engageable with the carrier to push the carrier in the direction of said operative movement, and means for imparting a series of reciprocatory movements to said member to cause operative movements of said tool, said movement-imparting means being constructed and arranged to transmit continuous pressure to said pushing member during each operative movement of the pushing member.

2. A welt indenting machine, comprising a welt

indenting tool, a carrier for said tool mounted for operative movement to enable the tool to press against a work piece, a plunger unconnected with said carrier but engageable with the carrier to

5 push the carrier in the direction of said operative movement, a guide for said plunger, a continuously driven member rotating about an eccentric axis, a connecting rod mounted at one end on said rotating member, and means connecting the other end of said connecting rod to said plunger for causing the plunger to reciprocate and thereby to operate said tool.

3. An indenting machine, comprising a work support, an indenting tool, a carrier for said indenting tool mounted for heightwise movement

15 and arranged to enable the indenting tool to rest freely upon a work piece on said work support, a member guided for heightwise reciprocation, said reciprocable member being engageable in its

20 down strokes with said carrier to transmit pressure impulses to said indenting tool and being unconnected with said carrier to avoid lifting the tool from the work piece on the up strokes of the reciprocable member, and operating means

25 constructed and arranged to impart to the reciprocable member a force which increases during each down stroke.

4. An indenting machine comprising an indenting tool, a support upon which work may be presented to said tool, a carrier for said indenting

30 tool movable in a direction toward and away from said work support to enable the tool to press the work with variable pressure against the work support, a rapidly reciprocating member engageable in the course of each of its advancing strokes with said carrier to urge the tool against the work on the work support, and means for limiting the movements of the carrier in the direction of the return strokes of the reciprocating member.

5. An indenting machine comprising an indenting tool, a support upon which work may be presented to said tool, a carrier for said indenting

35 tool movable toward and away from said work support to enable the tool to press the work with variable pressure against the work support, and means for operating said carrier to urge the tool repeatedly toward the work support, said operating means comprising a plunger arranged to move into abutting engagement with said carrier, a toggle connected to the plunger, and means

45 for straightening and breaking the toggle in rapid succession to cause the tool to exert a rapid series of pressure impulses upon the work.

6. An indenting machine comprising an indenting tool, a support upon which work may be presented to said tool, a carrier for said indenting

55 tool, a pivot upon which said carrier is mounted for swinging movement about an axis spaced from said work support to enable the tool to press the work with variable pressure against the work support, a reciprocable plunger arranged to enter into abutting engagement with said carrier to impart a pressure impulse to the carrier upon each advancing stroke of the plunger, and a toggle mechanism connected to the plunger for causing a rapid reciprocation of the plunger whereby the carrier is caused to transmit a rapid series of pressure impulses to the tool.

7. An indenting machine comprising an indenting

70 tool, a support upon which work may be fed to said tool, a carrier for said tool, a pivot upon which said carrier is mounted for swinging movement to enable the tool to be moved bodily, the axis of said pivot extending in a plane parallel to the path of feed of a work piece on said work

support and having a direction oblique to that of the path of feed to give the movement of the tool a component in the direction of said path of feed and a component which presses the work piece against the work support, and means for swinging said carrier about said pivot to cause the tool to exert upon the work a pulsating pressure having a feeding component and a pressure component.

8. In a machine of the class described, a tool operable upon a work piece by pressure, a carrier for said tool mounted for movement to enable the tool to press against the work piece, and a stop for limiting the movement of the carrier beyond the necessary range of operation, said stop and a cooperating portion of the carrier being magnetically attractive to each other to hold the carrier against the stop and thereby to prevent rebound when the work piece is withdrawn.

9. In a machine of the class described, a tool operable upon a work piece by pressure, a work table for supporting the work piece under the pressure of said tool, a carrier for said tool mounted for movement to enable the tool to press against the work piece, operating means unconnected with said carrier but engageable with the carrier to push the carrier toward the work table in a direction to cause the tool to press against the work piece, and a stop engageable by the carrier to hold the tool off the work table when a work piece is not interposed between the tool and the work table, said stop and a cooperating portion of the carrier being magnetically attractive to each other to hold the carrier against the stop and thereby to prevent rebound when the work piece is withdrawn from beneath the tool.

IRVING E. BOOTH.
